UNITED STATES PATENT OFFICE.

RICHARD CURTIS AND WILLIAM HENRY RHODES, OF MANCHESTER, COUNTY OF LANCASTER, ENGLAND.

ROVING-FRAME, &c.

SPECIFICATION forming part of Letters Patent No. 323,857, dated August 4, 1885.

Application filed September 26, 1884. (No model.) Patented in England November 6, 1880, No. 4,560.

To all whom it may concern:

Be it known that we, RICHARD CURTIS and WILLIAM HENRY RHODES, subjects of the Queen of Great Britain, residing at Manchester, in the county of Lancaster, England, have invented a new and useful Improvement in Roving-Frames, &c., (for which we have obtained a patent in Great Britain, No. 4,560, bearing date November 6, 1880,) of which the following is a specification.

Our invention relates to slubbing, intermediate, and roving or jack frames, (also called "speeders;") and the object of our invention is to provide improved mechanism for imparting a gradually-decreasing speed to the bobbins, so that the bobbins shall always draw the slubbing or roving from the front rollers at a uniform speed, notwithstanding the increase of the diameter of the yain on the bobbins as they become filled.

In performing our invention we dispense with the ordinary "jack-in-the-box" or differential motion usually employed to communicate motion from the driven or lower cone-drum to the bobbins and substitute the improved mechanism hereinafter described and illustrated in the accompanying drawings, in which—

Figure 1 is an elevation, and Fig. 2 is an end view, of part of a roving-frame or speeder, to which our improvements are applied. Fig. 1^a is an end view, and Fig. 2^a is an elevation, of the roving-frame, showing the rack and ratchet to shift the strap on the cone-pulleys, and the shaft with its skew-gears to rotate the bobbins, both figures showing parts broken away. Fig. 3 is a longitudinal sectional elevation of our improved mechanism, and Figs. 4 and 5 show either side of the disk *j* with the wheels that revolve therewith. Fig. 5 also

shows a section of the wheel *n*.

a is the ordinary driving-shaft, and *b* is the wheel fixed on the shaft, which imparts motion to the spindles, as usual. *c* is the twist-wheel, also fixed on the driving-shaft, which drives the top cone-shaft, *c'*, by the wheels *c*² and *c*³. On the shaft *c'* is a wheel, *c*⁴, that drives the drawing-rollers by a wheel, *c*⁵, fixed on the front roller-shaft. The top cone drives the lower cone at a decreasing speed by a strap, *d*. The roving-frame is started with the strap *d* at the large end of the top cone, and so

drives the lower cone at a gradually-decreasing speed as strap *d* is traversed from the larger to the smaller diameter of the top cone by a strap-guide, *d'*, actuated by a rack, *s*, and ratchet-wheel *t* in the ordinary manner. When the bobbins are filled with roving or yarn, the strap *d* will have been moved to the small end of the top cone. Before restarting the roving-frame the strap *d* is moved back again to the large end of the top cone. To effect this the bottom cone is raised by a worm, and wheel *x* actuated by the hand-wheel *y*, and rack *s* is caused to traverse after releasing the ratchet *t* by turning the hand-wheel *u* on the shaft *u'*. The lower cone transmits motion by the wheels *d*² *d*³ and *d*⁴ *d*⁵ to the wheel *e*, which forms part of our improved mechanism for transmitting motion to the bobbins. The wheel *e* is fixed to the sleeve *f*, which is loose on and is turned in the same direction as the driving-shaft *a*. On the other end of the sleeve *f* is fixed the wheel *g*, which gears into and rotates a double carrier-wheel, *h* *h'*, which turns on a stud, *i*, fixed to the disk *j*, which is fixed on the driving-shaft *a*. One part of the carrier-wheel *h'* gears into a wheel, *k*, fixed on a short shaft, *l*, which turns in a bearing formed in a boss on the disk *j*. At the other end of this shaft *l* is fixed the wheel *m*, which gears into an internally-toothed wheel, *n*, which is loose on the driving-shaft *a*. The wheel *n* has a long boss, on which is fixed the wheel *o*, that transmits motion through the carrier-wheel *p* to the wheel *q*, fixed on the bobbin-shaft *r*. The wheel *q* also gears into and drives a similar sized wheel, *q'*, on the front bobbin-shaft, *r'*. On the bobbin-shafts *r* *r'* are the "skew" bevel-wheels *r*² *r*³, which rotate the bobbins in the usual manner.

We make the wheel *o* with about one-tenth more teeth than the wheel *b*, to cause the first lap on the bobbins to be wound at the desired speed. The wheels *e* and *g* turn in the same direction as the driving-shaft *a*, but at a slower speed. The wheel *g* causes the double carrier-wheel *h* *h'* to rotate at the same time that it revolves round the shaft *a*. The smaller wheel of the double carrier-wheel *h* *h'* rotates the wheel *k* and the wheel *m* as they revolve round the shaft *a*, and the wheel *m* gears into and turns the wheel *n*, which transmits motion

through the wheel *o*, carrier *p*, and wheel *q* to the bobbin-shaft *r*.

As the shaft *a* is driven at a uniform speed, and as the wheel *g* is caused to rotate in the 5 same direction, but at a gradually-decreasing speed, the wheel *m* will be caused to make a slight and increasing backward rotary movement as it revolves round the shaft *a*, (in the direction indicated by the arrows on Figs. 4 10 and 5,) thus communicating a decreasing speed to the internally-toothed wheel *n*, and by the wheels *o*, *p*, and *q* to the bobbin-shaft *r*, thus causing the bobbins to turn at the desired speed to draw the yarn at a uniform speed 15 from the front rollers.

What we claim as our invention, and desire to secure by Letters Patent of the United States, is—

The combination, with the driving-shaft *a*, 20 and the disk *j*, fixedly secured thereon, and provided with a stud, *i*, and shaft *l*, of the wheel *e*, loosely mounted on the drive-shaft *a*, a wheel,

g, connected therewith, means for rotating said wheel *e* and its wheel *g*, the double carrier-wheel *h* *h'* on stud *i*, the wheels *k* *m* at 25 opposite ends of the shaft *l*, the wheel *g*, operating the wheel *h*, and the wheel *h'*, operating the wheel *k*, the internally-toothed wheel *n*, mounted loosely on the driving-shaft *a*, and the wheel *o*, connected with the wheel *n*, sub- 30 stantially as set forth.

The foregoing specification of our improvement in mechanism for imparting a decreasing speed to the bobbins of slubbing, intermediate, and roving or jack frames signed by us 35 this 21st day of August, 1884.

RICHARD CURTIS.

WILLIAM HENRY RHODES.
